UNITED STATES PATENT OFFICE.

HENRY J. GAISMAN, OF NEW YORK, N. Y.

DESIGN FOR A BELT-BODY.

SPECIFICATION forming part of Design No. 33,442, dated October 23, 1900.

Application filed July 30, 1900. Serial No. 25,251. Term of patent 7 years.

To all whom it may concern:

Be it known that I, HENRY J. GAISMAN, a citizen of the United States, residing in New York city, borough of Manhattan, State of New York, have invented and produced a new and original Design for a Belt-Body, of which the following is a specification, reference being had to the accompanying drawings, forming part hereof, wherein—10 Figure 1 is a face view of a body portion of a belt embodying my design, and Fig. 2 is a side view of the same.

As shown in the drawings, the leading or material feature of my design consists in the 15 configuration and ornamentation of a belt-body, in which one edge diverges from a central point toward the ends and the opposite edge is slightly concave, the surface of the belt having ribs extending substantially parallel with the adjacent margin or edge.

20 The letter A in the drawings indicates a belt-body which is wider at its central portion than at its ends, and one edge from the central portion a extends toward the ends on diverging lines a', which, as shown, lead in ²⁵ an upward direction, and the opposite edge b is slightly curved or concave, the deepest portion of the curve being at the central portion of the belt-body, and the surface of the belt-body is embellished by ribs c d, producing ³⁰ a corded effect, said ribs extending substantially parallel with the edges a' b, respectively.

I do not claim the configuration or shape of the belt-body irrespective of the ornamentation.

35

I claim—

The design for a belt-body, substantially as shown and described.

HENRY J. GAISMAN.
